REFLECTIVE BICYCLE PEDAL

Carlton P. Pawsat and Robert F. Humlong, Maysville,
Ky., assignors to Wald Manufacturing Company, Inc.,
Maysville, Ky.

Filed Nov. 13, 1970, Ser. No. 25,956

Term of patent 14 years

Int. Cl. D12—16

U.S. Cl. D90—14

FIG-1

FIG-3

FIG-2

FIG-4

FIG-5

FIG-6

FIG-8

FIG-7

FIG-9

FIG-10

FIG. 1 is a top perspective view of one end of a reflective bicycle pedal showing our new design.

FIG. 2 is a top perspective view of the other end thereof.

FIG. 3 is an elevational view as seen from the left side of FIG. 1.

FIG. 4 is a side elevational view of FIG. 2.

FIG. 5 is a view similar to FIG. 1 showing a modified form thereof.

FIG. 6 is a view similar to FIG. 1 showing a third modified form thereof.

FIG. 7 is a top perspective view of the other end of FIG. 6.

FIG. 8 is an elevational view as seen from the left side of FIG. 6.

FIG. 9 is a side elevational view of FIG. 7.

FIG. 10 is a view similar to FIG. 6 showing a further modified form thereof.

The sides opposite to those shown in FIGS. 5 and 10

are mirror images thereof, and the rear surfaces are the same as shown in FIGS. 2 and 7.

We claim:

The ornamental design for a reflective bicycle pedal, as shown and described.
